UNITED STATES PATENT OFFICE.

CARL HERZOG, OF HARRISON, NEW JERSEY.

OIL-FIRING SYSTEM.

Application filed April 14, 1924. Serial No. 706,276.

This invention relates to improvements in oil firing systems on boilers for locomotives, marine engines, stationary engines or on boilers for heating systems or the like.

It is the principal object of my invention to provide a firing system for such boilers installed within the boiler itself in order to utilize the entire heat developed without any loss caused for instance by the exhaust of the hot gases of combustion through the stack.

Another object of the invention is to provide a firing system of the character described above which does away with the customary stack and positively prevents the formation of smoke or cinders, etc.

A further object of the invention is the provision of a boiler of this type with means for automatically extinguishing the heating flame as soon as the pressure exceeds a certain maximum in order to prevent boiler explosions and their disastrous consequences.

Further objects and advantages of the invention will become more fully apparent as the description thereof proceeds, and will then be specifically pointed out in the appended claims.

In the accompanying drawings forming a material part of this disclosure:

Figure 1 is a longitudinal sectional view of a boiler equipped with a firing system constructed according to the present invention.

Figure 2 is an end view of the boiler.

Figure 3 is a transverse sectional view of the same.

Figure 4 is a detail view of the burner and ignition system.

Figure 5 is a longitudinal vertical section through a pressure regulator.

Figure 6 is a front elevation of the pressure regulator.

Within a boiler 10 of convenient type another boiler 11 is located, and within this boiler 11 the heating pipe proper or vaporizing retort 12 is arranged which is heated from an oil burner 13 of any well known construction for steam operation.

The retort 12 is arranged to heat water contained within boiler 11 and the steam generated escapes through the pipe 14 into the pressure regulator generally indicated at 15. The steam is then mixed within the burner 13 with a sufficient quantity of oil

to ensure a perfect combustion within retort 12 on account of the presence of a sufficient quantity of oxygen carried by the steam and present in the mixture.

The exhaust gases escape through pipe 16 which is in communication with the boiler 10.

The water level within the boiler 10 is indicated at 17 at about half the length of pipe stem 16. It will be clear that the hot exhaust gases will tend to displace the water within pipe 16 and boiler 10, and will give up their heat to the water contained therein. The steam thus generated will escape from the boiler through the elbow 18 of the steam dome 19 of boiler 10 and will be passed to the engine to be operated in the customary manner.

As no steam is originally present within the inner boiler 11, this boiler must be supplied with auxiliary air or steam, and with this end in view, steam or air under pressure is introduced through the conduit 20, while valve 21 is closed, and valve 22 open. It is clear that the steam and air under pressure must be supplied under a pressure of above 2 atm., which is then automatically reduced to suit the purpose by the pressure regulator 15.

The steam or air under pressure passes through valve 22, the T-piece 23 and is then transformed within the pressure regulator 15 to any desired degree of pressure; it mixes within the burner 13 with the fuel oil which is supplied to the burner through the supply pipe 24.

The combustible mixture is ignited by means of a suitable fuse of any well known construction or the like introduced through the bore or opening 25, whereupon said bore 95 or opening is closed by any customary means suitable for this purpose.

The hot gases of combustion give their heat up to the retort 12 which will heat the water contained within boiler 11. The exhaust gases will leave the retort through the pipe stem 16 and during their passage through the water contained within boiler 10 will give up their heat to the water contained therein whereupon they mix within the steam dome of boiler 10 with the steam contained therein.

The steam within boiler 10 must be allowed to escape until boiler 11 starts to operate or to generate its own steam in order 110

to prevent the presence of a pressure surplus which would impede the proper operation of boiler 11 and retort 12.

As soon as a sufficient quantity of steam is generated within the boiler 11, i. e. steam of more than 2 atm. pressure, the valve 21 is opened and the valve 22 is closed. The steam generated within boiler 11 will now pass through the pipe conduit of valve 21, pass the same, and T-piece 23, and will then be reduced within the pressure regulator 15 to the desired degree. The steam thus reduced will mix within oil burner 13 with the oil to form a perfectly combustible mixture which will be combusted within the retort 12. The exhaust gases escape through pipe stem 16 into the steam dome of boiler 10.

The heating surface of boiler 11 must be large enough to allow the maintenance of a higher pressure within boiler 11 than in boiler 10. This is necessary because a greater pressure should be maintained for allowing a proper working of the retort 12 and in order to allow the escape of the hot exhaust gases from this retort through boiler 10 without encountering any retarding or impeding resistance which would be injurious to the proper working of the system. The water within boiler 10 and within the pipe stem 16 will act to separate the flame within retort 12 from the steam within boiler 10.

If the pressure within boiler 10 rises above the prescribed maximum, the water will be pressed through pipe stem 16 into the retort 12 and extinguish the flame therein, so that boiler explosions are positively prevented. A man-hole 26 is provided for allowing a proper cleaning of the retort 12 and the boilers. As illustrated in Figures 2 and 3, 27 is the manometer for boiler 10, 28 the manometer for boiler 11, 29 is the water gage for boiler 10 and 30 that for the boiler 11. 31 indicates the steam conduit from boiler 10 to the pressure regulator 15, while 32 indicates the water level within boiler 11, and 17 the water level within boiler 10.

In Figures 5 and 6 a steam regulator is illustrated in longitudinal sectional view and in front elevation respectively.

The steam enters the regulator 15 through conduit 33, and reaches the piston chamber 34 through the openings 35, acting upon the piston 37 to press the same downwardly. The piston rod 38 is kept in elevated position by means of a spring 39 wound around the rod and having a predetermined strength. If now steam pressure prevails which is greater than the compressive strength of the spring, the piston 37 will be displaced, the opening 35 will be partially closed, and the pressure will evidently be reduced.

The spring must be carefully adjusted for a predetermined degree of initial pres-

sure. In order to maintain a higher pressure within the retort 12 than in boiler 10, the steam chamber 34 is provided below piston 37 which is in communication with the boiler 10 by means of the conduit 31. The pressure prevailing within this chamber 34 will assist the spring 39 by its tendency to press the piston 37 toward the top and to enlarge the operative extent of the openings 35, so that the pressure is increased and the steam leaves the conduit 40 under a pressure greater than that prevailing in boiler 10 or plus the so-called initial pressure.

The lower end of spring 39 rests upon a boss 41 held in place by a plug 42 within the housing 43 and screwed into the regulator body 15, and 44 and 45 are adjusting nuts permitting a regulation of the tension of spring 39 to any desired degree.

The operation of the device will be entirely clear from the above description without any further explanation.

It will be clear that changes may be made in the general construction of my device and in the construction of its minor details as fall within the spirit and scope of the appended claims.

Having thus described my invention, what I claim as new and desire to secure by Letters Patent is:

1. An oil firing system for boilers comprising in combination with a pair of boiler shells, one spaced wholly within the other to heat the outer of said shells, of a heating retort within the inner shell, means for heating said retort, connections between said inner shell and said heating means whereby steam generated in said inner shell is mixed with fuel oil in said heating means, a valve in said connection for maintaining a higher pressure within the inner shell than in the outer shell to prevent extinguishing of the flame within said retort, and means for automatically extinguishing the flame within said retort if the pressure in the outer shell exceeds a predetermined maximum.

2. An oil firing system for boilers comprising in combination with a pair of boiler shells, one spaced wholly within the other to impart heat to the outer shell, each being adapted to contain water, a heating retort within the inner shell, a burner within said retort, connections between the inner shell and said burner whereby steam from said inner shell may be mixed with fuel oil in said burner, means in said connection to maintain a higher pressure within the inner shell than in the outer of said shells, and means for automatically extinguishing the burner within said retort if the pressure in the outer shell exceeds a predetermined maximum.

In witness whereof I have affixed my signature.
